UNITED STATES PATENT OFFICE.

THOMAS MONTGOMERY, OF GREENOCK, SCOTLAND, ASSIGNOR OF ONE-HALF TO JAMES McNEIL, OF GREENOCK, SCOTLAND.

TIME-CHECKING MACHINE.

1,106,958.

Specification of Letters Patent. Patented Aug. 11, 1914.

Application filed April 11, 1913. Serial No. 760,381.

To all whom it may concern:

Be it known that I, THOMAS MONTGOMERY, a subject of the King of Great Britain, residing at Greenock, Renfrewshire, Scotland, 5 have invented certain new and useful Improvements in Time-Checking Machines, of which the following is a specification.

This invention relates to time checking machines for checking the time of workmen and others of the class in which the 10 workmen's checks are passed through an aperture and then guided by means of a deflector or chute into boxes, compartments, drawers or other receptacles for the various 15 times, this deflector being moved automatically by mechanism suitably constructed and arranged in connection with and operated from the clock.

The object of the present invention is to 20 provide improved and simplified mechanism for operating the deflector.

The mechanism is so constructed that, at a predetermined time (or times) an arm or equivalent is moved to set the deflector so 25 as to deliver the checks into a certain receptacle and then, by means of a specially constructed cam or snail, the arm is allowed to move back, at quarter hour or other intervals, so as to shift the deflector in such 30 manner as to deliver the checks into "late" receptacles.

Preferably, in carrying out the invention there is attached to the hour spindle of the clock (which may be of any suitable and 35 well known construction) a pin wheel having holes spaced at hour intervals therein, and a pin or pins can be inserted in one or more of these holes respectively in a manner so as to set the deflector for a predetermined 40 time or times. For instance, two pins may be inserted in the wheel, one to set the deflector for 6 a. m. and another to set the deflector again for 10 a. m. or three pins may be inserted, one to set the deflector for 45 6 a. m., one at 10 a. m. and one for 1 p. m.

In order that the invention may be clearly understood I have hereunto appended an explanatory sheet of drawings whereon is shown, by way of illustration or example, 50 one mode of constructing the apparatus. The essential parts of the apparatus only are shown, the other parts of the time checking machine being of a suitable and well known construction.

55 Figure 1 is an elevation of the deflector

operating mechanism with the pin wheel indicated in dotted lines. Fig. 2 is a view of the pin wheel and its connections with the arm *h* broken off. Fig. 3 is a plan view of the mechanism.

A is the plate of the clockwork. B the clock dial indicated in dotted lines. C the boxes, compartments or drawers for the checks. D the deflector, E the hour hand of the clock.

In the arrangement shown, I fit on the hour spindle *a*¹ a pin wheel *a* and this wheel performs one revolution in 12 hours. It has a series of 12 holes *b* therein, one for each hour of the day.

c is the pinion for driving the pin wheel *a*. *d*¹ is the minute spindle and *d* the minute wheel or cannon pinion which drives, through the wheel *e*, the pinion *c*. On the minute wheel is a snail *f* which is shown in full lines at Fig. 1 and is dotted at Fig. 2. This snail along with the minute wheel performs one revolution per hour. On the pin *g* is a sleeve *g*¹ to which an arm *h* is secured, the outer end of this arm being connected by means of a link *i* with the arm *j* of the deflector *D*, which latter is pivotally carried on the pin *k* in the usual manner. The checks are inserted by the workmen into the machine through the slot *l* and drop down as usual on to the deflector. On the sleeve *g*¹ is a second arm *m* which is a spring arm and has a lateral projection *m*¹ on it which works on the periphery of the snail *f*. The arm *h* has also a projection *h*¹ on it with which the pins of the pin wheel engage. The deflector *D* may be made as usual but has, preferably, a back portion *D*¹, the function of which will be hereinafter referred to.

I prefer to provide for late periods each representing a $\frac{1}{4}$ of an hour interval and there may be four or five of such periods. With the snail *f* as shown on the drawings, there are five periods represented by the steps 1, 2, 3, 4, 5. As will be seen, the step 1 overhangs the step 5, a gap being left between the two. The boxes or compartments C are also numbered 1, 2, 3, 4, 5, corresponding to the steps on the snail.

Assuming it is desired to check the time at 6 o'clock in the morning, then a pin *n* is inserted in the pin wheel at the hole for setting the deflector for 6 o'clock and a $\frac{1}{4}$ hour or other short interval before the clockwork mechanism comes to the 5th hour, *i. e.* about 110

1½ hours before 6 o'clock or the time for which it is desired to set the deflector, this pin (n) contacts with the projection h^1 of the arm h and gradually lifts said arm and 5 also the arm m up until, after an hour, i. e. about $\frac{1}{4}$ to 6 o'clock the arm h will have been raised sufficiently to bring the deflector to the position indicated by full lines at D (Fig. 1) so that checks dropped into the slot 10 l will be deflected into the drawer or compartment 1, and the arm m will have been raised sufficiently to allow the projection m^1 thereon to rest on the part 1 of the snail. Immediately after 6 o'clock the projection 15 m^1 of the arm m will have traveled over the part 1 of the snail and it will then fall on to the step 2 with the result that the arm h will fall into the position h^2 , (Fig. 1) and simultaneously the deflector D will assume 20 the position marked 2^x , (as indicated in dotted lines), so that a workman arriving after 6 o'clock will have his check deflected into the drawer or compartment No. 2. When a $\frac{1}{4}$ past 6 is reached the projection m^1 will 25 drop again on to the step 3 of the snail with the result that the arm h will assume the position h^3 and the deflector will assume the position indicated in dotted lines at 3^x with the result that the time checks will 30 now fall into the box or compartment 3. When $\frac{1}{2}$ past 6 is reached the projection m^1 will again drop on to the step 4 of the snail with the result that the arm h will move into the position h^4 and the deflector will 35 assume the position 4^x thereby directing the time checks into the compartment 4. When a $\frac{1}{4}$ to 7 o'clock is reached the projection m^1 will fall on to the step 5 with the result that the arm h will assume the position h^5 40 and the deflector will assume the position 5^x , that is to say, the time checks will now fall on the part D^1 of the deflector and will be directed into the compartment 5. The deflector will remain in this position so that 45 all workmen arriving at or after a $\frac{1}{4}$ to 7 o'clock will have their time checks directed into the compartment 5.

If it is desired to have the apparatus operate at 6 o'clock and at 10 o'clock then two 50 pins would be inserted in the pin wheel, the one (n) to set the deflector for 6 a. m. in the manner before stated and the other (n^1) to set the deflector for 10 a. m. The deflector would be in the position indicated at 55 5^x from 7 o'clock until say a $\frac{1}{4}$ to 9 o'clock and when a $\frac{1}{4}$ to 9 o'clock arrived the second pin n^1 would again gradually lift up the arm h until, after about an hour or $\frac{1}{4}$ to 10 o'clock the said arm would be in its topmost position 60 ready for the same movements to be given to the deflector at intervals as occurred at between 6 and 7 o'clock. In order to extricate the projection m^1 from the gap between the overhanging part of the step 1 and the 65 step 5 of the snail, the arm m is made of

spring metal and the projection m^1 is slightly beveled so that it will readily disengage.

It will be obvious from the foregoing, that by suitably arranging pins in the pin wheel, 70 the time can be checked for any hour or hours of the day or night.

Instead of using a special pin wheel I may, of course, use the hour wheel of the clock and provide it with a series of holes 75 for pins (n).

If desired, there may be different snails say one for giving $\frac{1}{4}$ hour intervals, another for giving $\frac{1}{4}$ hour intervals combined with shorter intervals, or otherwise, as considered 80 advisable, and these snails would be removable and interchangeably fitted.

One great advantage of the mechanism hereinbefore described is that it can readily be applied to ordinary clockwork mechanism. 85

Having now fully described my invention, what I claim and desire to secure by Letters Patent is:—

1. In a time checking machine in which 90 checks are deflected into a plurality of receptacles, means for operating the deflector, comprising, in combination with the hour and minute spindles of a clockwork mechanism, a pivoted arm means connecting said arm and the deflector, a wheel secured to the hour spindle of the clockwork mechanism and having holes therein, a pin adapted to be inserted in one of said holes and to move said arm, at a predetermined time to set the deflector to deliver the checks, as they are inserted in the machine, into one of the receptacles, a stepped cam on the minute spindle of the clockwork mechanism, a second arm fast to the first arm, and a projection on said second arm adapted to engage the periphery of said cam and by engaging step after step thereof, to allow the pivoted arm to move the deflector at intervals to deliver the checks into other of the 100 receptacles. 105

2. In a time checking machine in which 115 checks are deflected into a plurality of receptacles, means for operating the deflector, comprising, in combination with the hour and minute spindles of a clockwork mechanism, a pivoted arm, means connecting said arm and the deflector, a wheel secured to the hour spindle of the clockwork mechanism and having holes therein, pins adapted to 120 be inserted in said holes and to move said arm, at predetermined times, to set the deflector to deliver the checks, as they are inserted in the machine, into one of the receptacles, a cam secured on the minute spindle and having a plurality of steps formed thereon, the last step being in a recess below the first step, a second and spring arm fast to the first arm, a beveled projection on said second arm adapted to engage the periphery 125 130

of the cam and, by engaging step after step thereof, to allow the pivoted arm to move the deflector at intervals to deliver the checks into other of the receptacles.

5 3. In a time checking machine in which checks are deflected into a plurality of receptacles, means for operating the deflector, comprising, in combination with the hour and minute spindles of a clockwork mechanism, a pivoted arm, a projection on said arm, means connecting said arm and the deflector, a wheel secured to the hour spindle of the clockwork mechanism and having holes therein, pins adapted to be inserted in said holes and each adapted to engage the projection on said pivoted arm and move same so as to set the deflector to deliver the checks, as they are inserted in the machine, into one 10 of the receptacles, a stepped cam on the minute spindle of the clockwork mechanism, a second arm fast to the first arm, a projection on said second arm adapted to engage the periphery of said cam and, by engaging step after step thereof, to allow the pivoted arm to move the deflector at intervals to deliver the checks into other of the receptacles

15 20 25

4. In a time checking machine in which

checks are deflected into a plurality of receptacles, means for operating the deflector, comprising, in combination with the hour 30 and minute spindles of a clockwork mechanism, a pivoted arm, a projection on said arm, means connecting said arm and the deflector, a wheel secured to the hour spindle of the clockwork mechanism and having holes therein, pins adapted to be inserted in said 35 holes and each adapted to engage the projection on said pivoted arm and move same so as to set the deflector to deliver the checks, as they are inserted in the machine, into one 40 of the receptacles, a stepped cam on the minute spindle of the clockwork mechanism, a second arm fast to the first arm, a projection on said second arm adapted to engage the periphery of said cam and, by engaging step 45 after step thereof, to allow the pivoted arm to move the deflector at intervals to deliver the checks into other of the receptacles

In testimony whereof I affix my signature in presence of two witnesses.

THOS. MONTGOMERY.
